METHOD OF PREPARING QUINONE

Nels Harold Vagenius, Chicago, Ill., and Rollo J. Kidd, Warrensville, Ohio

Application October 10, 1934, Serial No. 747,726

7 Claims. (Cl. 204—9)

Our invention relates to a method of producing quinones, the phenol addition products thereof and hydroquinones, and more particularly to an improved method of producing such compounds by the oxidation of the phenols. In producing quinones or hydroquinones it has heretofore been proposed to oxidize aromatic hydrocarbons, such as benzene, by passing an electric current through an emulsion of benzene in an aqueous solution of a salt or mineral acid, the oxygen formed at the anode serving to oxidize the hydrocarbon. Such processes, however, are difficult to control and various other compounds may be formed, such as phenols and polyphenols, or if the oxidation is continued for a sufficient length of time, the desired products are oxidized to complete disintegration in preference to the hydrocarbons.

Attempts have also been made to oxidize the phenols, particularly phenol itself. Reports of investigations show, however, that in addition to quinone and phenoquinone other oxidation products are formed, such as resinous bodies, polyphenols, catechol, fatty acids, etc. In view of the side reactions which take place and the numerous other products which are formed it has heretofore been impractical to produce quinone, the phenol addition products thereof or hydroquinone, commercially by such processes.

We have made the discovery that if phenol is dissolved in an aqueous solution of a mineral acid or an acid salt in certain specified proportions and the temperature maintained within a specified range, phenols may be effectively and commercially oxidized to quinone or the phenol addition products thereof, depending upon the concentration of the phenol and the temperature at which the reaction takes place. The quinone, or the phenol addition products thereof, may then be reduced to hydroquinone.

While we do not desire to be limited in this respect, our process is particularly adapted for producing quinones or the phenol addition products thereof by the electrochemical oxidation of the phenols. Our invention also contemplates in its more specific form the production of quinone or the phenol addition products thereof by the oxidation of the phenols and their subsequent reduction preferably by electrochemical means, to form hydroquinone.

It is therefore an object of our invention to provide an improved process of producing quinone or the phenol addition products thereof by the oxidation of phenols.

Another object of our invention is to provide an effective process of preparing quinone, the phenol addition products thereof, or hydroquinone, by means of which such compounds may be economically and practically produced in an economical manner.

A further object of our invention is to provide an improved process of producing quinone or the phenol addition products thereof by the electrochemical oxidation of phenol by means of which high uniform yields of such compounds may be obtained.

Another object of our invention is to provide a process of producing quinone or the phenol addition products thereof from an electrolyte containing phenol by means of which the concentration of the phenol is maintained substantially constant and the quinone or a phenol addition product thereof is quickly removed from the oxidation zone as soon as it is formed.

A further object of our invention is to provide an improved method of preparing hydroquinone by means of which quinone or a phenol addition product of quinone is first formed by the oxidation of a phenol and the hydroquinone is formed by the electrochemical reduction of the quinone or a phenol addition product thereof.

Another object of our invention is to provide an improved solution or electrolyte in which quinone or a phenol addition product thereof is insoluble at certain specified temperatures.

A still further object of our invention is to provide an improved process in which a phenol addition product of quinone is formed by the oxidation of a phenol, the product is subjected to electrochemical reduction to produce hydroquinone and phenol, and the phenol is again utilized in the process.

Although we do not desire to be limited in this respect we prefer to utilize the electrochemical method of oxidizing the phenols to produce quinones or the phenol addition products thereof, and this method has accordingly been illustrated in the accompanying drawing in which Fig. 1 is a diagrammatic view of an apparatus for producing quinone or the phenol addition products thereof; and Fig. 2 is a similar view of an apparatus for producing quinone or a phenol addition product thereof, and reducing it to hydroquinone.

In practicing our invention in accordance with the method illustrated in the drawing, phenol or a homologue of phenol, such as cresol or xylol, is dissolved in the electrolyte composed of a dilute solution of a mineral acid which does not react with the phenol, such as sulphuric acid or phosphoric acid. Solvents which are neutral or slightly acid may also be employed, such as the alkali bisulphates. For example, sodium bisulphate, aluminum sulphate and potassium aluminium sulphate have been found suitable. The electrolyte may be present in amounts ranging from 5% to 20%, although we do not desire to be limited in this respect as good results have been obtained when the electrolyte is present in 60

- amounts as low as 1%. As the electrolyte we prefer to utilize an aqueous solution containing approximately 10% of sulphuric acid. As illustrated in the drawing, the electrolyte which contains the dissolved phenol is placed in a suitable plating tank 2 that is capable of resisting the solvent action of the electrolyte or any of the oxidation products which are formed. The plating tank or cell is provided with an anode 3 which is preferably formed of rolled or polished lead. The cathode 4 may be formed of copper or bronze gauze having approximately twenty meshes per square inch. In preparing quinone or phenoquinone a porous diaphragm 5 is preferably interposed between the electrodes although this is not essential. If it is desired to produce quinhydrone, however, the porous diaphragm should be omitted; otherwise a precipitate containing undesirable products will be obtained. A direct current 20 is then passed through the electrolyte.
- The particular product which is formed will depend upon the temperature and the concentration of the phenol and whether a porous diaphragm is employed. If the concentration of the phenol is maintained low, for example, if not more than 1% is present and the temperature is kept below 12° C., the product will be composed principally of quinone, although some phenoquinone may be produced. If the concentration 30 of the phenol is increased, a greater amount of phenoquinone will be produced. When the concentration of the phenol in the electrolyte is present in amounts ranging from 2% to 5% and the temperature is maintained below 12° C. phenoquinone will be produced. It will therefore be seen that the concentration of the phenol in the electrolyte is a material factor in determining whether quinone, phenoquinone or a mixture of these two compounds is formed.
- 40 While we have enumerated certain concentrations of phenol and specified certain temperatures at which quinone, phenoquinone or a mixture thereof will crystallize from the electrolyte, we prefer to maintain the electrolyte at a temperature below 7° C. The temperature of the electrolyte should be above the freezing point and below 12° C. The most desirable temperature, however, is slightly above the freezing point, say from approximately 3° to 5° C., because the quinone or phenoquinone is less soluble in the electrolyte at low temperatures. Suitable means, such as coils 6 through which a cooling fluid or refrigerant is passed, may be provided to maintain the electrolyte at the desired temperature.
- 50 If it is desired to produce quinhydrone, the electrolyte is maintained at a temperature from approximately 12° to 17° C., preferably about 15° C. In producing quinhydrone it is also essential that the porous diaphragm be omitted.
- 60 In producing quinone, it is essential that the concentration of the phenol should be maintained below 1% and in producing the addition products of quinone, such as phenoquinone or quinhydrone, it is essential that the concentration of the phenol 65 in the electrolyte should be maintained below 5% and preferably below 3%; otherwise undesirable side reactions will take place.
- 70 During the passage of the current the quinone or phenol addition product thereof is removed from the zone of oxidation, filtered as indicated at 8 from the mother liquor which may be returned to the electrolyte by means of a suitable pump 9 and pipe 10, the crystallized product being collected in the receptacle 11.
- 75 Although the voltage and current density at

the anode may be varied within reasonable limits, we prefer to maintain the voltage below 3.5 volts. The current density at the anode should be approximately one ampere per twenty-eight square inches of surface.

To obtain uniform yields it is also desirable to maintain a substantially uniform concentration of the phenol in the electrolyte. As the quinone or phenol addition product thereof is produced and removed from the oxidation zone, additional phenol should be added from the supply tank 1. We have also found that the efficiency of the process may be improved by adding a small amount of a catalyst. For example, approximately one gram of chromium sulphate for each five hundred grams of electrolyte has been found suitable.

The quinone or phenol addition product thereof may, if desired, be reduced to hydroquinone by any of the usual processes. In accordance with 20 our invention the quinone or phenol addition product thereof is first formed by the method which has just been described and then reduced to hydroquinone by electrolytic reduction. The oxidation of the phenols to quinone or the phenol 25 addition products thereof and the subsequent reduction may be performed separately or the two processes may be combined as illustrated in Fig. 2 of the drawing.

As illustrated in Fig. 2, the apparatus utilized in 30 producing the quinone or phenol addition product thereof, is similar to that shown in Fig. 1 and the parts have consequently been designated by the same numerals. The quinone or phenol addition product thereof which is separated from the 35 mother liquor by filtration or other suitable means is introduced into the electrolyte 12a of an electroplating cell or tank 12. The electrolyte in the reducing step may be composed of a dilute solution of sulphuric acid. It is not necessary that all 40 of the quinone or the phenol addition product thereof should be in solution.

The cell 12 is provided with an anode 13 which may be formed of lead and a cathode 14 which may be formed of copper or bronze gauze similar 45 to that utilized in the oxidation cell. The current is then passed through the electrolyte utilizing approximately two volts and substantially the same current density as that employed during the oxidation step. The temperature of the electrolyte 50 is maintained at approximately 60° C. and if necessary suitable coils 15 through which a heating fluid may be passed are provided for this purpose.

The efficiency of the reduction step may also be improved by adding a suitable catalyst, such as 55 titanium sulphate or tin sulphate. Approximately two grams of the catalyst for each one hundred grams of electrolyte has been found satisfactory. The contents of the cell are then treated with a small amount of charcoal and allowed to cool.

If quinone or quinhydrone are first prepared they will be reduced to hydroquinone during the reduction step. If phenoquinone is first prepared, during the reducing step the quinone is reduced to hydroquinone and the phenol floats upon the 65 surface of the hydroquinone and may be removed by any suitable means or method, such as by skimming or decantation, or as illustrated in the drawing the phenol may be returned to the supply tank 1 by means of a pump 16 and pipe 17. 70 The hydroquinone which separates in the form of crystals may then be removed from the cell 12 and separated from the mother liquor at 18 by filtration or other suitable means and collected in the receptacle 19. The mother liquor may then be 75

returned to the cell 12 by pump 20 and pipe 21.

As previously stated, we do not desire to limit our invention to the electrochemical method of producing quinone or the phenol addition products thereof. For example, the phenol in the concentration specified may be dissolved in a dilute solution of phosphoric or sulphuric acid, say a solution containing 1% to 20% of such acid or preferably from 5% to 20%, and the oxidation 5 may be performed by means of suitable oxidizing agents such as ozone, hydrogen peroxide or per-sulphuric acid.

By oxidizing the phenol and maintaining the concentration of the phenol and the temperature 15 within the range specified during the electrochemical method of oxidation, either quinone or a phenol addition product thereof, such as phenoquinone or quinhydrone, will precipitate and may be intermittently or continuously removed 20 from the sphere of the reaction.

By utilizing the essential features of our invention it is also possible to prepare the phenol addition products of quinone. For example, if phenol is added to or mixed with a chilled aqueous 25 solution of quinone or an aqueous solution containing an electrolyte such as sulphuric or phosphoric acid, and the temperature is maintained below 12° C., or preferably below 7° C., phenoquinone will separate. In a like manner, 30 by adding an aqueous solution of hydroquinone, or an aqueous solution of hydroquinone containing an electrolyte, to an aqueous solution of quinone, or mixing the solutions together and maintaining the temperature between 12° and 17° 35 C., quinhydrone may be precipitated. It will therefore be seen that the quinhydrone may be readily converted into hydroquinone, or hydroquinone may in turn be converted into quinhydrone.

40 From the foregoing specification it will be apparent that we have provided a practical and effective method of producing quinone or the phenol addition products thereof by the oxidation of phenols which may be commercially and 45 economically utilized in preparing the desired product.

It will also be seen that we have provided an economical and practical method of electrochemically oxidizing the phenols by means of which 50 quinones, phenoquinones, quinhydrone and hydroquinones may be produced in an effective and commercial manner.

It will also be apparent that we have provided an improved process by means of which phenols 55 may be readily oxidized to quinone or the phenol addition products thereof without forming large quantities of other oxidation products and that the products thus obtained may be readily and effectively reduced to hydroquinone by electrochemical means.

It will also be understood that we have provided a method by means of which quinones or the phenol addition products thereof may be effectively converted into hydroquinones by electrochemical reduction.

It will be understood in the specification and claims that the term "quinone oxidation product of a phenol" is intended to include not only quinone itself but also the phenol addition products thereof.

To those skilled in the art many modifications and widely differing embodiments of our invention will suggest themselves without departing

from the spirit and scope thereof. Our disclosure, description and examples given herein are purely illustrative and are not intended to be in any sense limiting.

What we claim is:

1. The process of producing a quinone oxidation product of a phenol, at least part of which is obtained as a precipitated solid, which comprises passing a direct electric current through an aqueous solution of an acidic inorganic electrolyte which is a solvent for the phenol and which contains a substantial amount but less than three per cent of the phenol in solution while maintaining the electrolyte at a temperature ranging from 0° C. to 17° C. 15

2. The process of producing a quinone oxidation product of a phenol, at least part of which is obtained as a precipitated solid, which comprises passing a direct electric current through an aqueous solution of an acidic inorganic electrolyte which is a solvent for the phenol and which contains a substantial amount but less than three per cent of the phenol in solution while maintaining the electrolyte at a temperature ranging from 0° C. to 17° C., and removing the 20 oxidation products from the zone of reaction as they are formed. 25

3. The process of producing a quinone oxidation product of a phenol, at least part of which is obtained as a precipitated solid, which comprises 30 passing a direct electric current through a dilute aqueous solution of sulphuric acid containing a substantial amount but less than three per cent of phenol to oxidize the phenol while maintaining the electrolyte at a temperature 35 ranging from 0° C. to 17° C.

4. The process of producing phenoquinone, at least part of which is obtained as a precipitated solid, which comprises passing a direct electric current through an acidic inorganic electrolyte 40 which is a solvent for phenol and which contains more than one per cent and less than three per cent of phenol in solution while maintaining the electrolyte at a temperature ranging from 0° C. to 7° C. 45

5. The process of producing quinone which comprises passing a direct electric current through an aqueous solution of an acidic inorganic electrolyte which is a solvent for phenol and which contains a substantial amount but 50 less than one per cent of phenol while maintaining the temperature of the electrolyte between 0° C. and 7° C.

6. The process of producing a mixture of quinone and phenoquinone, at least part of which 55 is obtained as a precipitated solid, which comprises passing a direct electric current through an aqueous solution of an acidic inorganic electrolyte which is a solvent for phenol and which contains from one per cent to three per cent of phenol in solution while maintaining the temperature of the electrolyte between 0° C. and 7° C.

7. The process of producing quinhydrone, at least part of which is obtained as a precipitated solid, which comprises passing a direct electric 65 current between electrodes placed in an acidic inorganic electrolyte which is a solvent for phenol and which contains phenol in substantial amounts but less than three per cent while maintaining the temperature of the electrolyte 70 between 12° C. and 17° C.
